Act. 593

P. A. Palmer of Leroy, N. Y.
Letters Patent No. 593. Dated Augt 30th, 1853.

The schedule referred to in these Letters Patent, & making part of the same.

To all whom it may concern:

Be it known that I, P. A. Palmer of the town of

20
Leroy, in the County of Genesee and State of New York, have invented or produced a new and original design of a cast iron frame for a milk stool, and I do hereby declare that the following is a full, clear, and exact description of the same, reference being had to the annexed drawing, making a part of this specification.

The design of my milk stool frame consists of two rings or frames A and B, connected together by a neck C, the surface of the larger ring being ornamented with a vine and leaf D, running around it.

Having thus described my design of milk stool frame, what I claim as new and desire to secure by Letters Patent, is—

The ornamental design and configuration of a milk stool, such as herein described and represented.
